UNITED STATES PATENT OFFICE.

THOMAS H. GALLAGHER, OF CARNEGIE, PENNSYLVANIA.

PUMP FOR ARTESIAN WELLS.

SPECIFICATION forming part of Letters Patent No. 735,661, dated August 4, 1903.

Application filed September 30, 1901. Serial No. 77,033. (No model.)

To all whom it may concern:

Be it known that I, THOMAS H. GALLAGHER, a citizen of the United States of America, residing at Carnegie, in the county of Allegheny and State of Pennsylvania, have invented certain new and useful Improvements in Pumps for Artesian Wells, of which the following is a specification, reference being had therein to the accompanying drawings.

10 My invention comprises a valve-casing consisting of lower and upper members detachably secured together, the lower member having a neck at its lower end, with which a section of the pump barrel or tube is connected, 15 a partition dividing the lower member into inlet and outlet chambers and having a central rod-opening, an annular flange within the lower end of the central rod-opening provided with radial recesses, an upwardly-extending collar surrounding the central rod-opening and an annular series of crifices each provided with a lower valve-recess and located between the collar and wall of the lower member, a guide-sleeve located with 25 its upper end in the collar and having radial locking lugs or fins at its lower end beneath the partition and an annular flange seating on the annular flange of the partition, a cap having a central rod-opening and secured to 30 the collar, an upper member with which a section of the pump barrel or tube is connected and receiving the upper end of the collar and having a lower end formed with an annular series of upper valve-recesses located 35 above the lower valve-recesses spaced from the partition and fitting in the upper end of the lower member, and valves adapted to play in the space between the lower and upper valve-recesses, as hereinafter described and 40 claimed.

In order that my invention may be fully understood, I will proceed to describe it with reference to the accompanying drawings, in which—

45 Figure 1 is in part a side elevation and in part a vertical longitudinal section of my improvement in pumps for Artesian wells. Fig. 2 is a top plan view of the lower member, the guide-sleeve and ball-valves being omitted. 50 Fig. 3 is a side elevation of the guide-sleeve. Fig. 4 is a bottom view thereof.

10 is the working barrel or tube of a pump

for Artesian wells, having an interiorly-screw-threaded upper end 11, receiving the exteriorly-screw-threaded neck 12 of the lower member 13 of a valve-casing. This lower member 13 has an interiorly-screw-threaded upper end 14 and a partition 15, providing a lower inlet-chamber 16 and an upper outlet-chamber 17.

The partition 15 is formed with a central rod-opening 18 and an annular flange 19, having radial recesses 20 and surrounding the central rod-opening 18, an annular series of orifices 21, each having a lower hemispherical valve-recess 22 and located between the central rod-opening 18 and the wall of the lower member 13, and an exteriorly-screw-threaded collar 23, surrounding the central rod-opening 18.

24 represents a series of ball-valves normally seated in the lower valve-recesses 22 in the upper outlet-chamber 17. Within the collar 23 and projecting downwardly into the lower inlet-chamber 16 is a depending guide-sleeve 25 for the pump-rod 26, provided with radial wedge-shaped locking lugs or fins 27 at its lower end and an annular supporting-flange 28, located contiguous to the locking lugs or fins and seating on the annular flange 19. The guide-sleeve 24 is seated within the collar 23 by bringing the locking lugs or fins 27 into position over the radial recesses, which will permit its lower end to pass through the central rod-opening 18. The space between the upper end of the guide-sleeve 25 and the collar 23 provides a chamber 29, into which suitable material may be placed to furnish a packing for the pump-rod 26. This chamber 29 is closed by an interiorly-screw-threaded flanged cap 30, having a central rod-opening 31 and secured to the collar 23.

32 is the upper member of the casing, having a central chamber 33 and an exteriorly-screw-threaded lower end 34 fitted in the interiorly-screw-threaded upper end 14 of the lower member 13, having upper hemispherical valve-recesses 35 for the reception of the ball-valves 24, which play across the outlet-chamber 17 from their spaced recesses.

Having thus described my invention, the following is what I claim as new therein and desire to protect by Letters Patent:

A pump for Artesian wells comprising a

lower member formed with a neck at its lower end, a partition dividing the lower member into a lower inlet-chamber and an upper outlet-chamber, and having a central rod-opening, an annular flange located at the base of the central rod-opening and having radial recesses, an upwardly-extending collar providing an extension to and surrounding the central rod-opening, and an annular series 5 of orifices each having a hemispherical recess and located between the collar and the wall of the lower member, a guide-sleeve having its upper end located within the central rod-opening, and its lower end depending 10 from the partition and formed with radial locking-fins and an annular flange spaced from the locking-fins and seating on the annular flange of the partition, a cap having a 15

central rod-opening and secured to the collar, an upper member having a lower end fitting 20 the upper end of the lower member, and formed with a central chamber receiving the collar and cap of the partition and an annular series of hemispherical valve-recesses located above the lower valve-recesses, and 25 spaced from the partition, and ball-valves adapted to seat in the valve-recesses and to play across the upper chamber of the lower member.

In testimony whereof I affix my signature 30 in the presence of two witnesses.

THOMAS H. GALLAGHER.
